(57) **CLAIM**

The ornamental design for an apparatus for filling and packing pre-formed conical cigarette wrappers, as shown and described.

DESCRIPTION

FIG. 1 is a top front right view of our design; FIG. 2 is a front elevational view of our design; FIG. 3 is a right side elevational view of our design, the left side is a mirror image thereof;

FIG. 4 is a rear elevational view of our design;

FIG. 5 is a top plan view of our design;

FIG. 6 is a bottom plan view of our design; and,

FIG. 7 is an exploded front elevational view of our design for apparatus for filling and packing pre-formed conical cigarette wrappers.

Dashed lines represent unclaimed environment and form no part of the claimed design.
